EARTH-BORING APPARATUS AND MOTOR
THEREFOR

Clyde E. Bannister, Bartlesville, Okla.

Application December 13, 1939, Serial No. 308,978

23 Claims. (Cl. 255—4)

This invention relates primarily to assemblies that are inclusive of an oscillating motor and it is of especial value in earth-boring equipment.

Some features disclosed in the present application are described and broadly claimed in my patent Reissue No. 19,397, granted December 18, 1934, as a reissue of my original Patent No. 1,965,563, granted July 10, 1934.

The chief objects of the present invention are to provide an oscillating motor having some or all of the advantages of (1) adaptability for use with a grit-bearing motive fluid, such as the recirculated drilling fluid used in the drilling of oil wells, without excessively rapid wear of the motor parts by the gritty fluid; (2) large amplitude of oscillation for a tool, such as a drill bit, driven by the motor; (3) avoidance of dead-center stoppage of the fluid-driven shaft-impeller; (4) hydraulically operated valves, with elimination of valve springs; (5) permissibly large port areas; (6) provision for the use of a large diameter driven shaft in a motor of moderate over-all diameter; (7) provision for the use of large bearings; (8) employment of a pilot valve for hydraulic operation of the main motor valve; (9) avoidance of load on the pilot valve bearing; and (10) the employment of a slip-in liner for the motor casing, for ready replacement of the lining in case of wear.

Of the accompanying drawings:

Fig. 1 is a side elevation, with parts sectioned and broken away, of a preferred embodiment of my invention as applied to non-vertical earth boring.

Figs. 2, 3 and 4 are side elevations of valve parts that are shown in Fig. 1.

Fig. 5 is a longitudinal axial section of the casing of the motor with motor parts therein shown in elevation.

Fig. 6 is a section on line 6—6 of Fig. 1.

Fig. 7 is a section on line 7—7 of Fig. 5.

Fig. 8 is a section on line 8—8 of Fig. 5.

Fig. 9 is a section on line 9—9 of Fig. 5.

Fig. 10 is a section on line 10—10 of Fig. 1.

Fig. 11 is an axial section on line 11—11 of Fig. 10.

Fig. 12 is a side elevation, with parts sectioned and broken away, of a modified type of assembly embodying certain features of my invention and adapted for the drilling of wells.

Fig. 13 is a similar view of another embodiment adapted for well drilling.

Referring to the drawings, the apparatus of Figs. 1 to 11 comprises a cylindrical motor casing 10 which is screw-threaded at 11 to a heavy in-

ertia barrel 12 adapted to sustain by its inertia the reaction of the shaft-oscillating motor. The inertia barrel has secured within it, as by means of cap-screws 13, 13, a segmented lead weight 14 adapted, by reason of gravity, to resist rotation of the assembly as a whole and thus maintain it in proper working position in non-vertical drilling.

Screw threaded at 15 upon the rear end of the inertia barrel 12 is an inertia-barrel extension in the form of a cylindrical end-closure member 16 formed at its closed rear end with a fluid-inlet neck 17 to which is coupled a hose 18 for supplying fluid to the motor through the space in the inertia barrel 12 that is not occupied by the weight 14.

The assembly comprises a bit 19 secured upon the forward end of a hollow, oscillating motor shaft 20 which, near the bit, is journaled in the motor casing 10 by means of a radial-and-thrust bearing 21 and also is journaled at 22 in a bulk-head member 23, secured in the motor casing 10 by means such as the cap screw 24, and the shaft also is journaled at 25 in a bulk-head-and-fluid-abutment member 26 (Figs. 1 and 6) which is secured in the motor casing 10 as by means such as the cap screw 27.

Slidably fitting within the motor casing 10 and abutted by shoulders formed on the members 23 and 26 is a removable cylindrical casing-liner 28 of which the inner face (see the lower part of Fig. 1) has a sealing fit against an oscillating shaft-impeller 29 which is shown in Fig. 7 as being integral with the motor shaft 20.

The bulk-head-and-fluid-abutment member 26 is formed with an axially long, transversely segmental portion 26a adapted to sustain the reaction of pressure fluid forced between it and the shaft-impeller 29 and the hollow shaft 22, at longitudinally spaced apart positions, is formed with two fluid-inlet ports 30, 31 closely adjacent and at opposite sides of the shaft-impeller 29, and with two fluid-outlet ports 32, 33, closely adjacent and at opposite sides of the shaft-impeller 29.

For putting the said inlet ports, and thus also the chambers at the two sides of the shaft-impeller 29, in communication with the pressure-fluid-chamber in the inertia barrel 12, and for putting the outlet ports in communication with the fluid-discharge passage, which is through the forward end of the hollow motor shaft 20 and through the bit 19, a hollow, oscillatory slide valve member 34 rotatably fits within the hollow motor shaft 20 and is formed with a supply port 35

adapted to be brought into registry with the shaft's port 30, as in Fig. 1 or Fig. 7, and with a supply port 36 adapted to be brought into registry with the shaft's port 31.

Internally the valve member 34 is provided, at a position forward of the ports 35, 36, with a transverse partition or bulk-head 37 (Fig. 1) and forward of the partition 37 the valve member 34 is formed, at a circumferential position half-way between those of the ports 35, 36, with an exhaust port 38 adapted to be brought into registry with the shaft's outlet port 33 when the valve's supply port 35 is brought into registry with the shaft's inlet port 30, and to be in registry with the shaft's outlet port 32 when the valve's supply port 36 is in registry with the shaft's inlet port 31.

Rearwardly the motor shaft 20 projects a little beyond the bulk-head-and-fluid-abutment member 26 and upon its projecting end portion is secured by means such as the set-screw 39 a cup-shaped pressure-chamber member 40 provided with a threaded end-closure member 41.

The valve member 34 extends with a sealing fit through the end closure member 41 and a bulk-head member 42 which is secured in the motor casing 10 by means such as the cap-screw 43 and within the pressure-chamber member 40 the valve member 34 is formed with annular shoulders 44, 45 abutting respectively the end of the motor shaft 20 and the closure member 41 to hold the valve member in position axially.

In that region also the valve member 34 is formed with fluid-inlet ports 46, 47 opening on opposite sides of a valve impeller 48 formed integrally with the valve and internally the cup-shaped pressure-chamber member 40 is provided with a fluid-abutment 49 to sustain the reaction of fluid-actuating the valve-impeller 48, the fluid-abutment 49 being, through the pressure-chamber member 40, rigid with the motor shaft 20.

The valve-impeller 48, integral with the valve 34, is free to rotate with relation to the motor shaft only through the small arc permitted by stops 50, 51 (Fig. 8) mounted on the forward end wall of the pressure-chamber member 40.

For supplying pressure fluid alternately to the fluid chambers on the respective sides of the valve impeller (Fig. 8) a hollow pilot-valve member 52 (Figs. 4, 8 and 9) comprises a stop-lug head portion 53 and a cylindrical valve portion 54 which is formed with a port 55 adapted to be brought into registry with the port 46, as in Fig. 8, when the stop-lug head portion 53 of the member 52, in one direction of rotation, is stopped by a stop-pin 56 mounted upon the bulk-head 42; and with a port 57 adapted to be brought into registry with the port 47 when the portion 53 of the member 52 is stopped, in the opposite direction of rotation, by the stop-pin 56.

The cup-shaped pressure-chamber member 40 is formed at appropriate positions with vent ports 58, 59 and for opening and closing them at proper times a valve sleeve 60 is mounted upon the member 40 and formed with vent ports 61, 62 and with shoulders such as the shoulder 63 (Fig. 5) adapted to strike a stop-pin 64 projecting from the bulk-head 26, at proper times.

The fit of the valve 34 within the motor shaft 20, the fit of the pilot valve 52 in the valve 34, and the fit of the valve-sleeve 60 upon the member 40, are such that all of these parts just mentioned rotate together, by reason of their frictional engagement, except as they are oscillated with relation to one another by the stops de-

scribed or by pressure fluid acting between the valve-impeller 48 and its fluid-abutment 49.

In the operation of the motor, assuming the shaft-impeller 28 to have moved clockwise, as viewed in Fig. 7, to the position in which it is there shown, contact of the stop-lug portion 53 of the member 52 with the stop-pin 56, as in Fig. 9, has brought the port 55 into registry with the port 46, as in Fig. 8, and pressure fluid passing through those registered ports, with the vent ports 59 and 62 out of registry and the vent ports 58, 61 in registry (Figs. 5 and 8), has quickly moved the valve-impeller 48 from the stop 51 to the stop 50, and this has put the valve port 35 in registry with the shaft port 30, as in Fig. 7, and the exhaust port 38 of the valve in registry with the outlet port 33 of the motor shaft. When the valve impeller 48 is thus quickly moved from the stop 51 to the stop 50, Fig. 8, the valve member 34 has carried with it in its rotation, by reason of the frictional fit, the pilot valve 52, and then both of them, by reason of the frictional fits, rotate with the motor shaft until near the end of its counterclockwise movement, at which time contact of the stop-lug 53 with the pin 56 and contact of one of the shoulders 63 (Fig. 5) with the pin 64 reverses the valve setting of the pilot valve 52 and valve sleeve 60, with the result that the main valve 34 is likewise reversed as to port registries, by the forcing of the valve-impeller 48 clockwise as viewed in Fig. 8, into contact with the stop pin 51, the valve 34 again frictionally carrying with it, clockwise, the pilot valve 52.

The cycle as just described is then repeated continuously so long as motive fluid is forced into the assembly.

As the reversal of registries of inlet ports and the reversal of registries of outlet ports controlling the movement of the valve-impeller 48 are simultaneous, and as the only resistance to oscillation of the valve 34 is a small frictional resistance, and as the shaft-impeller is still being driven in one direction until its direction has been reversed by reverse movement of the valve-impeller 48, and as any unbalance of fluid pressure starting the reverse movement of the valve-impeller 48 will inevitably complete its movement, the motor is without any dead-center position of its parts.

To cause the assembly to move forward as the boring operation proceeds and thus keep a suitable pressure upon the bit 19, a pair of respectively right-hand and left-hand hollow worms 65, 66, adapted to act against the earth-formation under the assembly, are slidably journaled at their rear ends in brackets such as the bracket 67 projecting from the member 16 and at their forward ends are formed with cup-shaped spring housings such as the housing 68.

Extending through the housing and slidably, but non-rotatably, fitting in the adjacent end portion of the hollow worm is a push bar 69 having secured thereon a spring-seating collar 70, between which and the spring-seating internal shoulder of the housing 68 is interposed a compression spring 71. For closing the housing 68 against the entrance of dirt, and permissibly for pre-loading the spring 71, a cup-shaped closure member 72 is screw threaded onto the spring-housing 68 and is formed with an internal end-flange 73 slidably fitting the push bar 69 and adapted to engage the spring-seating collar 70 for pre-loading the spring.

At its forward end each of the push bars 69 is journaled in a bracket such as the bracket 74 projecting from the motor casing 10 and the bracket

and the push bar are provided with respective thrust bearing members 75, 76 for transmitting to the motor assembly and the bit, through the compression springs 71, the force of the reaction of the worms 65, 66 against the earth formation.

For driving the right-hand and left-hand worms 65, 66 in opposite directions, in one half of each oscillatory cycle of the motor-shaft and bit, and in suitably short rotative movements, each push bar 69 has secured upon its forward end a bevel gear, 77, 78, which are meshed with respective bevel pinions 79, 80 secured upon respective short shafts 81, 82 which are disposed tangentially with relation to the motor casing and are journaled in respective brackets 83, 84 projecting from the latter. On the opposite end of these tangential shafts are secured respective small right-hand and left-hand worm gears 85, 86 which are meshed with respective right-hand and left-hand large worms 87, 88 which surround and are concentric with the motor shaft.

The worms 87, 88 are shown in Fig. 11 as being made as integral parts of a cup-shaped ratchet member 89 provided with a closure plate 90, a radial-and-thrust bearing 91 being interposed between the member 89 and the motor shaft 20 and a radial-and-thrust bearing 92 being interposed between the cover plate 90 and the motor shaft 20.

Fixedly secured upon the motor shaft 20, by means of a key 93 and set screw 94, within the enclosure thus provided, is a pawl-carrier 95 (Figs. 10 and 11) carrying spring-backed pawls 96, 96 coacting with ratchet teeth 97 formed on an interior annular face of the member 89.

The space in which the pawl carrier is mounted can be permanently packed with grease.

It will be manifest that with this construction each rotative movement of the motor shaft in one direction will effect the desirably short rotative movement of the worms 65, 66, in opposite directions for substantial balance of the rotative forces against the earth formation, and that as the worms 65 and 66 are thus caused to move forward with relation to the earth-formation with which they are engaged the compression springs (71) will be compressed and, through the spring-seating collars 70, push bars 69, thrust bearings 76-75 and brackets 74, will urge the motor-and-bit assembly forward and maintain a substantially steady pressure upon the bit.

The assembly shown in Fig. 12 is adapted for vertical drilling and comprises a shaft-oscillating motor operating upon the same principles as that above described, but a cable 98 is provided for suspending the assembly and a fluid-intake hose 99 and fluid discharge hose 100 are provided for passing pure or gritless motive fluid through the motor for avoidance of the wear that is caused by grit-laden fluid, the well, at the same time, being filled with weighted fluid to prevent caving.

The fluid-intake hose 99 leads to a pipe 101 which is suitably fixed within the inertia barrel assembly and is formed with an opening 102 for letting the fluid into the large internal space which leads to the motor.

The motor shaft, 20^a, has secured therein, below the lower end of the valve, 34^a, a partition 103 and the discharge of the motive fluid from the motor is through an opening 104 in a side of the motor shaft and an opening 105 in a side of the motor casing, 10^a, bulk-heads 23^a and 106 being provided in the casing respectively above and below these openings.

For sucking water upward through the bit, 19^a, and forcing it to the top of the well through the hose 100, an oscillatory pump assembly is associated with the lower portion of the motor shaft 20^a, this pump assembly comprising a fluid-abutment 107 mounted in the motor casing 10^a between the bulk-head 106 and a lower bulk-head 108, a pumping impeller 109 secured upon the motor shaft, and intake and outlet valves 110, 111 mounted in and communicating with passages extending through the bulk-heads 108 and 106 respectively.

The motor casing 10^a is provided with a still lower bulk-head 112 adapted to serve as one of the races for, and to keep fluid from, a radial-and-thrust bearing assembly 113, which can be grease-packed, the course of the pumped water being upward through the bit and through the lower end portion of the motor shaft, then through an opening 114 in the shaft into the space between the bulk-heads 112, 108, and from there through the intake valve 110.

Mounted in the fluid-abutment, 26^a, of the motor, and in the bulk-heads 23^a and 106, and communicating with the outlet valve 111 of the pump, is a pipe 115 which leads to the fluid-discharge hose 100.

This assembly of Fig. 12, in which fluid is sucked through the bit, insures a "clean hole" at all times and avoids repeated cutting of the material.

In the assembly shown in Fig. 13, a motor casing 116 has secured within it an inertia member 117 which is formed with a central fluid passage 118 which communicates at its upper end with a fluid conduit 119, which may be either a hose or a pipe and which is adapted to be connected, at the top of the ground, with the delivery pipe of a pump or, alternatively, with a fluid-conduit leading to a core-receiving settling tank.

The inertia member 117 is formed also with a fluid passage 120 which communicates at its upper end with a fluid conduit 121, which may be either a hose or a pipe and which is adapted to be connected, at the top of the ground, with the delivery pipe of the pump or, alternatively, with a fluid-conduit leading to the slush pit or settling basin.

At its lower end the fluid passage 120 communicates with a radially narrow, transversely arcuate passage 122 which is defined by a part of the motor casing 116 and a shell-like member 123 secured thereto as by welding, and the lower end of the passage 122 is open and is positioned near the bit, 124, for flow of flushing fluid and cuttings, from the bit, upward through the passages 122 and 120 and through the conduit 121 to the top of the ground.

In this embodiment the motor shaft, 125, and the valve, 126, therein, are of larger diameters, in relation to the over-all diameter of the assembly, than are the corresponding members in Fig. 1 or Fig. 12, and the partition, 127, in the valve 126, is centrally apertured and has rotatably mounted therein and sealed thereto by means of a sealing ring 128 a core-barrel 129.

The lower end of the core-barrel is fixedly secured in the bit 124, which in this embodiment as assembled in Fig. 13 is a bit of the core-taking type and is formed with apertures 130, 130 for the passage of flushing fluid from the exhaust of the motor, to the cutting faces of the bit.

At its upper end, which "stands proud" in a relatively large lower portion 118^a of the fluid passage 118, the core barrel 129 is provided with

a circumferential series of flap-valve members such as the members 131, 131, hinged as at 132, 132, the series of flap-valve members being adapted to prevent such free flow of motive fluid through the core-barrel 129 as to reduce excessively the fluid-pressure for actuating the motor, the motive fluid being compelled, by the flap valve members, to pass through the annular space surrounding the core barrel and thus to the valves, valve impeller and shaft impeller of the motor.

In the operation of this embodiment illustrated in Fig. 13, the fluid which drives the motor also serves as the flushing fluid and after passing downward through the conduit 119 and the passage 118 to the motor and then through the motor and through the passages 130 in the bit, passes upwardly to the top of the well through the passages 122 and 120 and the conduit 121, while the well, outside of the apparatus, stands full of non-circulating and preferably weighted fluid, which lessens the amount of caving of the wall of the well, especially when it is non-circulating, as in this arrangement, so that there is no washing away of the wall.

As the passages through which such upward flow occurs are of less cross-sectional area than the well-space surrounding the conduits 119 and 121, the upward velocity is greater than if the upward flow were through the said well space, and this high velocity is advantageous in avoiding sluggish removal of the cuttings from the vicinity of the bit and waste of time and of power in repeated cutting of dislodged particles.

As the bit 124 is oscillated by the motor and drills the well deeper a core is automatically taken in the core-barrel 129, and is usually well broken up by lateral movements or vibrations of the oscillating bit, so that the fragments can be forced to the top of well through the passage 118 and the conduit 119, by reversing the fluid circulation, the two conduits 119 and 121 being packed off at the top of well so that the fluid, pumped downward through the conduit 121, will be compelled to return to the top of the well through the conduit 119 and not through the space in the well surrounding the conduits.

The return flow of the reversed circulation, through the conduit 119, for washing out the core taken by the core-barrel, can be effected by closing conduit 121 at the top of the well and pumping fluid down through the well-space surrounding the conduits, the fluid being pumped through a packer at the top of the well, but the downward washing of the wall of the well which is incident to that procedure is undesirable.

In Figs. 14 and 15 is shown a suitable packer, which preferably is of the dual or "gas lock" type, for the passage of hose clamps or pipe couplings and "tool joints" into the hole without interruption of the drilling operation, one gate-valve packer 133 being located just above the ground level and the other one, 134, just above the derrick floor 135, the packers being opened one at a time for the passage of the hose clamps or the like, so that pressure can be continuously maintained in the well.

To make sure that the core is sufficiently broken to be pumped out as described, the assembly can be lifted a few inches off the bottom of the hole and then allowed to descend forcibly against it.

Preferably the inner diameter of the core-barrel is a little smaller than the inner diameter of the passage 118 and the conduit 119, as shown,

for free passage of core fragments upward through the conduit, and yet without such clearance as to permit an excessive amount of fluid to pass the core fragments.

5 To avoid taking so long a core that it would emerge from the upper end of the core-barrel and block the passage 118 against adequate downward flow of the motive fluid, one of the conduits 119 or 121 can be suitably marked at a determinate elevation above ground at the beginning of each core-taking operation and the core-taking operation stopped and the fluid circulation reversed, for pumping out the core, before the assembly has descended a distance equal to the length of the core-barrel.

After the core has been taken and pumped out as described, the circulation in the motor-driving direction is re-established and the cycle of operation as described is repeated.

20 If desired, the assembly can be quickly pulled out of the hole, in case the conduits 119 and 121 are of reelable hose, and a full-section drill bit can be substituted for the core-taking bit before drilling is resumed after the core-taking, but in

25 some localities it is desirable to take cores at all depths, or at least at all depths below a certain level, in which case the substitution of bits is not resorted to.

In all of these embodiments some or all of the advantages set out in the above statement of objects are obtained.

Various modifications are possible within the scope of my invention as defined by the appended claims.

I claim:

1. A motor comprising a casing, a fluid-abutment member therein, a hollow shaft to be oscillated, a shaft impeller rigid with said shaft, a valve member within said hollow shaft, the shaft and the valve member being formed with registerable ports, fluid-actuated means for controlling the movements of the said valve, and a pilot-valve for controlling the action of said fluid-actuated means.

45 2. A motor comprising a casing, a fluid-abutment member therein, a hollow shaft to be oscillated, a shaft impeller rigid with said shaft, a valve member within said hollow shaft, the shaft and the valve member being formed with registerable ports, fluid-actuated means for controlling the movements of the said valve, a pilot-valve for controlling the action of said fluid-actuated means, and stop means for controlling the action of the pilot valve.

55 3. A motor comprising a fluid-actuated impeller member, valve means controlling the admission of pressure fluid to said impeller member, fluid-actuated means controlling the action of said valve means, a pilot valve for controlling the action of said fluid-actuated means, and stop means for controlling the action of said pilot valve, the impeller member and the valve means having frictional driving engagement and the valve means and the pilot valve having frictional driving engagement.

60 4. A motor comprising an oscillatory hollow shaft, a shaft-impeller rigid therewith, a valve member fitted in the hollow shaft, a valve impeller rigid with said valve member, and means for applying pressure fluid alternately to the opposite sides of said valve impeller.

65 5. A motor comprising an oscillatory hollow shaft, a shaft-impeller rigid therewith, a valve member fitted in the hollow shaft, a valve impeller rigid with said valve member, and a pilot-

valve assembly for applying pressure fluid alternately to the opposite sides of said valve impeller.

6. A motor comprising an oscillatory hollow shaft, a shaft-impeller rigid therewith, a valve member fitted in the hollow shaft, a valve impeller rigid with said valve member, and a pilot-valve assembly for applying pressure fluid alternately to the opposite sides of said valve impeller, said pilot-valve assembly comprising a pilot-valve member fitted within the aforesaid valve member and adapted to be frictionally driven thereby, and stop means for said pilot-valve member.

7. A motor comprising a chamber-defining member, a fluid-abutment member and a valve-impeller therein, a sleeve-valve member on said chamber-defining member, the chamber-defining member and the sleeve-valve member being formed with registrable ports, means for conducting pressure fluid into said chamber-defining member, and means for putting the ports of the chamber-defining member and of the sleeve-valve member in and out of registry with each other.

8. Earth-boring apparatus comprising a motor of the shaft-oscillating type, a bit mounted upon the shaft of said motor, and means actuated by the motor and acting against the adjacent earth formation for urging the bit forward.

9. Earth-boring apparatus comprising a motor of the shaft-oscillating type, a bit mounted upon the shaft of said motor, means actuated by the motor and acting against the adjacent earth formation for urging the bit forward, and resilient force-transmitting means interposed operatively between the said means and the bit.

10. Earth-boring apparatus comprising a motor of the shaft-oscillating type, a bit mounted upon the shaft of said motor, and means actuated by the motor and acting against the adjacent earth formation for urging the bit forward, said means comprising a form adapted to react against the adjacent earth formation, and means for rotating the worm in alternate half-cycles of the shaft oscillations.

11. Earth-boring apparatus comprising a motor of the shaft-oscillating type, a bit mounted upon the shaft of said motor, and means actuated by the motor and acting against the adjacent earth formation for urging the bit forward, said means comprising a worm adapted to react against the adjacent earth formation, and means for rotating the worm in alternate half-cycles of the shaft oscillations, and resilient force-transmitting means interposed operatively between the worm and the bit.

12. Earth-boring apparatus comprising a motor of the shaft-oscillating type, a bit mounted upon the shaft of said motor, and means actuated by the motor and acting against the adjacent earth formation for urging the bit forward, said means comprising a worm adapted to react against the adjacent earth formation, means for rotating the worm in alternate half-cycles of the shaft oscillations, and resilient force-transmitting means and a worm-and-worm-gear drive interposed operatively between the worm and the bit.

13. Earth-boring apparatus comprising a motor, a bit mounted upon the shaft of said motor, a pair of oppositely pitched worms adapted to act against the adjacent earth formation for urging the bit forward, and means actuated by the motor for driving said worms in opposite directions, said means comprising a pair of op-

positely pitched worms concentric with the motor shaft.

14. Earth-boring apparatus comprising a motor of the shaft-oscillating type, a bit mounted upon the shaft of said motor, inertia means for sustaining the reaction of said motor, and means actuated by said motor and acting against the adjacent earth formation for urging the bit forward, the last said means comprising earth-engaging means and one-way drive means so interposed between the motor shaft and the earth-engaging means as to drive the latter intermittently but in the same direction, in alternate half-cycles of the oscillation of the motor shaft.

15. The combination of a fluid-actuated shaft-oscillating motor adapted to be lowered into an earth-boring, means for so lowering it, means for conducting motive fluid to the motor for actuating it while it is in the hole, a bit associated with and driven by the motor, the motor having its discharge orifice opening into the hole in the vicinity of the bit, and a pump associated with the motor and driven thereby for impelling a flow of the spent motive fluid past the bit.

16. The combination of a fluid-actuated shaft-oscillating motor adapted to be lowered into an earth-boring, means for so lowering it, means for conducting motive fluid to the motor for actuating it while it is in the hole, and a pump associated with the motor and driven thereby, the motor and the pump being of the oscillating type and comprising respective oscillating piston members spaced-apart lengthwise of and mounted upon the same shaft.

17. Earth-boring apparatus comprising a fluid actuated motor adapted to be advanced in a boring, a bit associated therewith and driven thereby, means for controlling its advance in the boring, a conduit for conducting motive fluid to the motor and a second conduit for conducting the motive fluid from the motor, a pump driven by the motor, the motor, pump, bit and conduits being so constructed and arranged that the motive fluid is constrained to flow through a part of the boring external to the motor in the vicinity of the bit and is forced through the second mentioned conduit by the pump.

18. Earth-boring apparatus comprising a fluid actuated motor adapted to be advanced in a boring, a bit associated therewith and driven thereby, means for controlling its advance in the boring, a conduit for conducting motive fluid to the motor and a second conduit for conducting the motive fluid from the motor, a pump driven by the motor, the motor, pump, bit and conduits being so constructed and arranged that the motive fluid is constrained to flow through a part of the boring external to the motor in the vicinity of the bit and upward through the bit and is forced through the second mentioned conduit by the pump.

19. Apparatus for taking a core and elevating it to the top of an earth-boring, said apparatus comprising a core-taking bit, a bit-oscillating motor for driving the same, means for forcing a fluid downward in the boring as a conduit, a conduit mounted in the boring for conducting fluid to the top of the same, the core space of the bit being in communication with the last mentioned conduit.

20. Earth-boring apparatus comprising a fluid-actuated motor having an axial passage through the same, a conduit for supplying actuating fluid to the motor from the top of the boring, a core-taking bit coaxial with said passage and driven

by said motor, a core-barrel associated with said bit and extending into said axial passage, and means for compelling a flow of fluid upward through said core barrel passage, and conduit passage to wash the core upward from said core-barrel to the top of the boring.

21. Earth-boring apparatus comprising a fluid-actuated motor having an axial passage through the same, a conduit for supplying actuating fluid to the motor from the top of the boring, a core-taking bit coaxial with said passage and driven by said motor, a core-barrel associated with said bit and extending into said axial passage, and valve means mounted on said core barrel for preventing excessive downward flow of fluid therethrough but permitting upward passage of fluid and of the core from the core-barrel, the parts being constructed and arranged for washing of the core from the core barrel and through said passage and conduit to the top of the boring.

22. Earth-boring apparatus comprising, as parts of a fluid actuated motor, a hollow motor

5 shaft, a hollow valve member movably fitted therein, a core-taking bit mounted on said motor shaft, and a core-barrel associated with said bit and extending at least into the hollow valve member, the motor comprising an oscillating piston and the valve member being so constructed and arranged as to supply actuating fluid to opposite sides of the piston alternately.

10 23. Earth-boring apparatus comprising a core-taking bit, a core-barrel associated therewith, a fluid actuated motor of the shaft oscillating type for driving said bit, a conduit for conducting motive fluid to said motor, parts of said motor defining a fluid passage from said conduit to the upper end of said core barrel and a branch conduit to the working parts of the motor, and means for compelling fluid to flow in a reversed direction through the core-barrel, the said passage and the said conduit for washing core material through the same.
